Cornelius De Bos,
By Thomas G. Orwig, Atty.

UNITED STATES PATENT OFFICE.

CORNELIUS DE VOS, OF BATTLE CREEK, MICHIGAN.

COMBINED PAPER-HOLDER, CALENDAR, AND BLOTTER.

SPECIFICATION forming part of Letters Patent No. 291,499, dated January 8, 1884.

Application filed March 24, 1883. (No model.)

To all whom it may concern:

Be it known that I, CORNELIUS DE VOS, of Battle Creek, in the county of Calhoun and State of Michigan, have invented a Paper-
Holder, Blotter-Carrier, and Calendar Com-
bined, of which the following is a specifica-
tion.

The object of my invention is to facilitate letter-writing and office business.

10 It consists in forming, arranging, and combining with a base or tablet a spring-clasp, a hinged blotter holder and carrier, and a per-
petual calendar, as hereinafter fully set forth.

Figure 1 of my accompanying drawings is a
15 perspective view of my complete device. Fig.
2 is an enlarged perspective view of the clasp
and paper-holder, the calendar, and a section
of the tablet. Fig. 3 is a longitudinal section,
and Fig. 4 a transverse section, of Fig. 2.
20 Jointly considered, these figures clearly illus-
trate the construction and operation of my
complete invention.

A represents the base-piece, in the form of
25 a tablet, that is preferably made of stiff pa-
per-board. It may vary in size as desired,
and can be covered with cloth, leather, or any
suitable book-cover material.

B is a blotter holder and carrier, that is also
30 preferably made of paper-board and suitably
covered.

C are common paper clips or fasteners,
stuck through the paper-board B near its ends
35 in such a manner that their ends can be read-
ily bent over the ends of one or more sheets,
D, of bibulous paper blotters, as clearly shown
in Fig. 1. The board B is shorter than the
base or tablet A, and hinged to one of the
40 edges of the tablet by means of a flexible
strap, similar to the manner in which two sec-
tions of a book-cover are connected.

E represents a spring-clasp (preferably made
45 of spring-wire) of common form, fixed to the
top and center of the tablet A by means of
rivets, or in any suitable way.

G is a rectangular block, preferably made of
wood. It has a section cut out from its cen-
50 ter to adapt it to receive and retain the clasp
E, fixed to the block and tablet in such a man-
ner that sheets of paper, when placed upon
the tablet and under the spring-clasp and
holder that projects below the block, will be

brought square relative to the tablet by abut-
ting against the fixed block and a wooden bar,
G², fixed to the edge of the tablet.

h h are vertical slots in the block, through
55 which the arms of the spring-clasp extend.

i is a groove or channel formed in the top
surface of the block to receive a slide.

m is an adjustable slide, preferably made of
paper-board, that extends through the chan-
60 nel i. It has numbers, or series of numbers,
corresponding with the number of days in a
month printed thereon.

n is a veneer cover fixed on the top of the
block. It has a slot, r, through which the
65 figures on the slide m are visible. At the side
of this slot, and in regular spaces correspond-
ing with the size of the numbered spaces on
the slide m, the names of the days of a calen-
70 dar week are printed or fixed upon the sur-
face of the cover n. On the opposite side of
the slot in the cover n, I print or fix the fol-
lowing rhyme:

Thirty days has September, April, June, and November; All the rest have thirty-one, Except the second month alone, To which we twenty-eight assign, Till leap-year gives it twenty-nine.	75

In the practical use of my invention I place
a number of letter-sheets squarely upon the
tablet, and under the spring-clasp and holder,
and one or more blotter-sheets in the hinged
80 blotter holder and carrier, and when I have
written upon the surface letter-sheet I turn
the hinged blotter-carrier upon it to bring the
surface of the blotter in contact with the fresh-
85 ly-written page, to absorb superfluous ink
and to prepare it for folding and removing.

To utilize the device as an advertising me-
dium, I print or paste business-cards, &c., up-
on the back of the blotter-carrier, and also
print advertising matter upon the blotters.

To utilize the lettered and numbered block
and adjustable slide as a calendar, I simply
90 adjust the slide each month so as to bring the
number 1 (one) parallel with the name of the
first day of each month printed at the side of
the slide, and then move it one space each
95 succeeding day of the month, so as to indi-
cate the name and number of each day in the
month during the passage of the month.

I am aware that blotters have been hinged to tablets; but my manner of forming a blotter-holder to adapt it for detachably connecting sheets of bibulous paper therewith at pleasure, and combining it with a paper-holding tablet provided with a head-block and side bar, within which to fold the blotter-holder upon sheets of writing-paper abutting squarely against the block and side bar, is novel and 10 advantageous.

I am also aware that blocks and clasps have been fixed to the ends of tablets, and that a sliding calendar-card has been moved in a base having a sight-opening to make the figures on 15 the cards visible in succession; but my manner of forming a head-block adapted to receive a sliding calendar-card and combining it with a paper-holding clip and tablet is novel and advantageous.

I claim as my invention—

1. The hinged blotter holder and carrier B, having paper-fastening devices C C, in combination with the base or tablet A, having a block, G, and spring-clasp E at its top end, and a bar, G², at its side, substantially as shown 25 and described, for the purposes specified.

2. As an improved article of manufacture, the combined tablet, blotter, and calendar, composed of the base A, hinged blotter and carrier B C C, the spring-clasp E, the block 30 G, having a channel in its top, side, and center, the adjustable slide m, and a cover, n, having a slot, r, substantially as shown and described, for the purposes specified.

CORNELIUS DE VOS.
